UNITED STATES PATENT OFFICE.

GEORGE WASHINGTON LINDSAY, OF GAINESVILLE, TEXAS.

COMBINED TORCH AND GAS-BURNER KEY.

SPECIFICATION forming part of Letters Patent No. 412,765, dated October 15, 1889.

Application filed November 21, 1888. Serial No. 291,430. (No model.)

To all whom it may concern:

Be it known that I, GEORGE WASHINGTON LINDSAY, of Gainesville, in the county of Cook and State of Texas, have invented a new and 5 Improved Combined Torch and Gas-Burner Key, of which the following is a full, clear, and exact description.

This invention relates to a device for lighting gas-burners and operating the cock of the 10 gas-burner, and has for its object to provide a combined torch and key by means of which the gas may be lighted without the flame of the torch coming in contact with the globe surrounding the burner and the cock of the 15 gas-burner readily taken hold of and operated.

The invention consists in a combined gas-torch and key constructed as hereinafter described and claimed.

Reference is to be had to the accompanying 20 drawings, forming a part of this specification, in which similar figures of reference indicate corresponding parts in all the views.

Figure 1 is a perspective view of the invention, partly broken away. Fig. 2 is a vertical 25 section of the upper end thereof, and Fig. 3 represents a modified form of key.

This invention has especial reference to burners having laterally-projecting cocks, and in connection therewith to avoid blackening 30 the globe of the burner.

In the construction of this invention the torch is formed with the main portion 1, having a chamber 2 to contain alcohol, preferably integral therewith, a wick-tube 3, projecting 35 at one side of the forked end 4, with cap 5, and the opening 6, with screw-cap 7. The main portion 1 is provided with a handle 8, which is preferably connected thereto by means of a square projection 9 on the main 40 portion 1, located in a correspondingly-shaped recess 10 in the handle and held by a set-screw 11. The handle 8 may be integral with main portion 1, if desired.

Instead of a rigid key, the torch is provided 45 with a movable key, consisting of an arm 12, pivoted in the forked end 4 by means of a thumb-screw 13. The arm 12 is held in the forked end 4 by friction, resulting from tightening screw 13 sufficiently to permit it to remain at any angle to the torch to which it

may be moved. The enlarged end 14 of the arm 12 is formed with cross-slots 15 of a size to engage a gas-burner cock or other cocks of any size. The arm 12 being adjusted to the desired position with reference to the torch 55 and the slotted end thereof engaged with a gas-burner cock, the flame of the torch will be located at a safe distance from the globe inclosing the burner.

In the modified form of key in Fig. 3 the 60 arm 16 is formed with an arm 17, projecting at right angles thereto and having its end provided with intersecting slots 18.

By means of this invention a combined torch and gas-burner key is provided which 65 may be used with Lungren and other burners, or any apparatus having a cock at the side, without interfering with the globe, and by means of which gas-burner cocks may readily be reached.

Having thus described my invention, what 70 I claim as new, and desire to secure by Letters Patent, is—

1. A combined torch and gas-burner key consisting of a handle having near its upper end 75 a reservoir, from which projects a wick-tube in close proximity to the extreme upper end of the handle, and an arm adjustably pivoted to the upper end of the handle above the reservoir and provided with slots for engaging 80 a gas-burner cock, substantially as described.

2. In a combined torch and gas-burner key, the combination, with a body portion having a forked upper end and provided with a reservoir below the same and a wick-tube projecting therefrom at one side of and in close proximity to the said forked end, of an arm pivoted in the forked upper end of the body and provided with slots to receive a gas-burner cock, substantially as described.

3. A combination torch and gas-burner key consisting of a torch having reservoir 2, wick-tube 3, forked end 4, and arm 12, pivoted therein on screw 13, and having enlarged end 14, with cross-slots 15, substantially as shown 95 and described.

GEORGE WASHINGTON LINDSAY.
